UNITED STATES PATENT OFFICE.

HASKELL W. BANKS, OF SAN DIEGO, CALIFORNIA.

AUTOMATIC AIR-PRESSURE GAUGE.

Application filed April 20, 1920. Serial No. 375,387.

To all whom it may concern:

Be it known that I, HASKELL W. BANKS, a citizen of the United States, residing at San Diego, in the county of San Diego and State 5 of California, have invented new and useful Improvements in Automatic Air-Pressure Gauges, of which the following is a specification.

This invention is an automatic pressure 10 gauge particularly adapted to be employed in connection with the air line used for filling a pneumatic tire.

It is an object of the invention to provide a gauge having improved means for relieving the pressure within the air line when 15 an adjusted predetermined pressure has been obtained in the tire.

It is a further object of the invention to provide a gauge of this character which may 20 form a part of the filling nozzle of the air line and one in which usual spring constructions are replaced by an adjustable weight, thereby obtaining a more accurate adjustment and a more positive action in the 25 gauge.

Further objects of the invention will be understood from the following description of the accompanying drawings in which;

Figure 1 is a top plan view of the invention applied to a usual filling nozzle.

Fig. 2 is a vertical longitudinal section through the same.

Fig. 3 is a longitudinal vertical section through the controlling valve of the gauge 35 showing the same in open position.

In the drawings I have shown the improved gauge as applied to and forming a part of the filling nozzle of an air line adapted for use for filling pneumatic 40 tires. It will be obvious, however, that the improved gauge may be made separate from the filling nozzle and employed in a variety of uses where it is desired to relieve pressure which exceeds a predetermined maximum.

The filling nozzle to which the invention is applied comprises the nozzle casing 1 having the laterally extending conduit 2 at its upper end and, preferably, formed integral 50 with the nozzle casing. This conduit, preferably, terminates in a reduced notched end 3 over which the end of a usual hose 4 is adapted to be received and clamped in position by any preferred clamping means 55 such as shown at 5.

The nozzle casing is centrally apertured as

shown at 6, this central aperture communicating with the conduit 2. A slidable valve member is received in the central aperture of the nozzle casing and is so arranged as to normally close the aperture through the nozzle casing and to open the same so as to permit the escape of air therefrom when pressure is applied against the end of the slidable valve member. As an instance of 60 this arrangement, the slidable valve member is shown as comprising a valve head 7 normally seated upon a shoulder 8 formed in the central aperture of the nozzle casing, a leak proof washer 9 being, preferably, inserted between the valve head and the shoulder.

The air from the hose 4 flows through the conduit 2 of the nozzle into the space surrounding the valve head 7, and when the valve head is in its normal closed position it will prevent the escape of the air past the shoulder 8. The valve head is, preferably, spring-seated upon the shoulder 8 as by a coil spring 10 positioned between the upper 65 end of the valve head and a removable end member 11 for the nozzle casing, this removable end member, preferably, having a threaded engagement 12 in the end of the nozzle casing and arranged to provide a 70 tight closure so that the air cannot escape through the end of the nozzle casing.

The valve head 7 is arranged to be actuated so as to be unseated from the shoulder 8 and permit the escape of air past said shoulder by an operating rod 13 extending from the valve head and, preferably, formed integral therewith, through the central aperture of the nozzle casing to the outer open end thereof. A central aperture 14 is provided in the operating rod, said aperture terminating short of the inner end of the rod and, preferably, communicating with the central aperture of the filling nozzle surrounding the operating rod as through a 80 transverse communicating port 15. By this arrangement it will be seen that when the valve head 7 is moved from its seat the air escaping past shoulder 8 is free to flow through the port 15 into the central aperture of the operating rod.

The outer end of the operating rod is provided with transverse ports 16 through which the air is then adapted to flow, being then arranged to be received in a pneumatic tire through the usual valve. The escape 100 of the air from the space formed by the cen-

tral aperture 6 of the nozzle casing through the space between the operating rod of the nozzle and the nozzle casing, is prevented by reducing the diameter of the central aperture through the nozzle casing so as to closely incase the operating rod, as shown at 17, and then enlarging this central aperture at the outer end of the casing to provide a space 18 in which suitable packing means are provided.

For this purpose an annular collar 19 may be provided upon the operating rod, the collar being received within the space 18 and a suitable packing washer 20 being provided between the collar and the nozzle casing, and a similar washer 21 being positioned at the outer face of the collar 19. This latter washer may be held in place by a sleeve 22 having a threaded engagement 23 over the outer end of the nozzle casing and being provided at its outer end with an inwardly turned lip 24 resting against the washer 21.

As previously stated, the valve head 7 and the operating rod carried thereby are normally yieldably held in position with the valve head seated. The washers 9, 20 and 21 are, preferably, of such resiliency as to permit a slight inward movement of the operating rod and the valve head carried thereby when the end of the filling nozzle is forced down over the end of the valve of a pneumatic tire, the valve stem of this valve impinging against the end of the operating rod to force the latter inwardly in the usual manner. Under these conditions the valve head will be unseated and air is then free to flow through the ports 16 in the operating rod into the valve of the pneumatic tire.

Means are provided for permitting the escape to the atmosphere of the air under pressure within the nozzle when the air pressure in the tire being filled has reached a predetermined pressure. For this purpose a second conduit 25 extends laterally from the casing of the filling nozzle, the casing of this conduit also, preferably, being formed integral with the casing of the filling nozzle.

The inner end of the conduit 25 communicates with the air space 6 surrounding the operating rod of the filling nozzle, and the outer end of this conduit communicates with a valve chamber 26. A sliding valve 27 is provided in the valve chamber and in normal closed position closes the end of the conduit 25, a washer 28 being, preferably, provided at this end of the valve. When the valve is moved away from the conduit 25 it is arranged to open said conduit to the atmosphere.

For this purpose a longitudinal aperture 29 may be provided extending through the valve 27 and arranged to communicate with the conduit 25 through the space in which the valve 27 is received when the valve is moved away from the end of conduit 25, as

shown in Fig. 3. The opposite end of the aperture 29 terminates in a transverse port 30 arranged to communicate when the valve 27 is moved to open position with a transverse port 31 provided in the end cap 32 adapted to be received over the end of the casing for conduit 25 and valve seat 26. The end cap 32 may be secured in position by a threaded engagement 33.

A gravity arm 34 is arranged to normally force the valve 27 to its seat for closing conduit 25 and to be moved by said valve so as to permit unseating movement of the latter when the pressure of the air through conduit 25 against the valve 27 exceeds the weight of the gravity arm 34.

As an instance of this arrangement the arm 34 may be pivotally connected to the end cap 32 as by a ball and socket connection between the arm and end cap. For this purpose the end of the arm 34 is shown as a hemispherical head 35 seated in a hemispherical recess 36 provided in the end cap, the outer end of the arm 34 being arranged to swing downwardly by the force of gravity no matter in what position the filling nozzle may be held. When the arm 34 is thus swung downwardly the lower edge of the inner face 37 of the head 35 will abut against the end of the valve 27, as clearly shown in Fig. 2, to force the valve inwardly to its seat over the end of conduit 25 thereby closing the valve.

When, now, the pressure within the tire being filled reaches a certain amount, the pressure of the air in the air space 6 and through the conduit 25 against the end of valve 27 will overcome the resistance of the gravity arm 34 and the valve 27 will be moved outwardly, the contact of the valve end against the lower edge of the head 35 swinging the arm 34 upwardly to the position shown in Fig. 3 and thereby providing sufficient space for the required longitudinal movement of the valve 27 in order to place port 30 in communication with port 31 and permit the escape of the air from conduit 25 past the valve head and through aperture 29 and ports 30 and 31 to the atmosphere. The inflation of the tire to any greater pressure is thus prevented and the sound of the escaping air will notify the operator that the tire is sufficiently inflated.

Means are, preferably, provided for adjusting the weight of the gravity arm 34 so as to cause the resistance afforded by said arm to be overcome at any predetermined pressure within the tire being filled. For this purpose a weight 38 is adjustable along the gravity arm 34, the outer end of the arm being, preferably, outwardly flared, as shown at 39, to prevent the removal of the weight from the arm, and the weight, preferably, snugly fitting on the arm so as to be frictionally held in adjusted positions. The arm

34 may be provided with suitable graduations represented at 40 so that the operator may readily set the weight 38 at any desired point to cause the escape of air from the nozzle through port 31 at any predetermined pressure.

Various changes may be made without departing from the spirit of the invention as claimed.

10 What is claimed is:

1. A device of the character described comprising a valve movable under pressure to relieve said pressure, and a gravity arm having a flat end surface and a convex bearing surface in rear of the same, said arm being pivoted at its bearing surface so that when in normal position the edge of the flat end of the arm will impinge against said valve for yieldably holding the same against the pressure controlled movement, said arm being arranged, at a predetermined pressure against said valve, to swing upon its bearing surface against the force of gravity so as to retract the flat end of the arm and thereby 25 permit movement of the valve.

2. A relief valve comprising a casing hav-

ing a valve chamber open at its inner end and a side outlet port, a valve slidably mounted in the valve chamber and having a port adapted to register with the side outlet port and adapted to receive pressure against its inner end and having a flat outer end, a cap upon the casing, and an arm extending through the casing and having a ball and socket connection therewith and having a flat inner end and engaging the flat outer end of the valve.

3. A relief valve comprising a valve casing, a valve movable under pressure to relieve said pressure and having a flat outer end and a gravity arm having a universal joint connection with the valve casing, and a flat inner end engaging the flat outer end of the valve so that when the arm is straight the valve is open and so that when the arm is moved in any direction the edge of the flat inner end will impinge against the flat outer end of the valve and move the valve to closed position.

In testimony whereof I have signed my name to this specification.

HASKELL W. BANKS.
